(57) **CLAIM**

I claim the ornamental design for a tongue depressor, as shown and described.

DESCRIPTION

FIG. 1 is a front view of a tongue depressor showing my new design;

FIG. 2 is a rear view of the tongue depressor shown in FIG. 1;

FIG. 3 is a top view of the tongue depressor shown in FIG. 1;

FIG. 4 is a bottom view of the tongue depressor shown in FIG. 1;

FIG. 5 is a right side view of the tongue depressor shown in FIG. 1, the left side being a mirror image thereof;

FIG. 6 is a front perspective view of the tongue depressor shown in FIG. 1; and,

FIG. 7 is a rear perspective view of the tongue depressor shown in FIG. 1.
